AMPLIFIER TUBE

Edward H. Yonkers, Jr., Chicago, Ill.

Application December 5, 1930, Serial No. 500,217

2 Claims. (Cl. 250—27.5)

This invention relates in general to electrical amplification apparatus and more particularly to that type of apparatus adapted to be employed in the amplification of high frequency electric currents especially as employed in radio frequency circuits, and the invention includes apparatus for amplifying more especially the high frequency alternating currents of a transmitting or receiving circuit, though it will be understood that the invention is capable of employment for other purposes, and, therefore, finds a wide field of utility.

10

The principal object of this invention is to provide amplification of alternating high frequency electric currents by the provision of an improved method of arranging the electrodes of a so-called three element gas-free vacuum tube and to accomplish the desired results without the objectionable "feed back" from the anode 20 to the cathode, therefore, eliminating the undesirable effects of inter-electrode capacitance.

More specifically, when a current is carried through gas-free space by ions all of the same sign, the potential gradient between the cathode and anode through the space containing the ions is not linear but assumes a curvature determined by the distribution and density of space-charge (as expressed by Poisson's equation). Under practical operating conditions, electrons being emitted from the cathode with finite velocities and the space-charge itself limiting the magnitude of the current, this curvature is such that there is a point of zero potential between the anode and cathode and a reversal of sign of the electrostatic field at this point so that the slope of the potential gradient at the cathode is negative. Thus, a control element or grid placed in this negative field between the cathode and the point of zero potential in the space-charge is electrostatically shielded from the anode. If the potential of the anode is gradually increased from zero to the saturation value, that is, the point where the rate of emission of electrons from the cathode alone determines the current, the density and distribution of space-charge so changes that the point of zero potential between cathode and anode moves toward the cathode becoming coincident with it at the saturation 45 value of current. The slope of the potential gradient at the cathode becomes zero at this point. It is desirable, therefore, that the control element and cathode be approximately equidistant from the anode if the shielding effect of the space-charge is to be adequately present

throughout the maximum useful variation in anode potential.

The foregoing and such other objects and advantages as may appear or are pointed out as this description proceeds are in the structural embodiment of the invention illustrated in the accompanying drawing, in which:

Figure 1 is a longitudinal sectional view of the amplifying apparatus including the improvements of my invention.

Figure 2 is a transverse section view taken on the line 2—2 of Figure 1 looking in the direction indicated by the arrows.

Figure 3 is a diagram curve characteristic of the device of this invention.

Figure 4 illustrates one circuit arrangement in which the device may be incorporated.

Figure 5 is a view similar to Figure 1 of an alternative form of the device.

The method of amplifying high frequency alternating electric currents of this invention includes the steps of bringing an electron emitting element to a state of incandescence in order or to form a cloud of electrons or negative ions or space charge. This forms the cathode of the amplifying device and as is well known to those skilled in the art, the negative electrostatic field being thus generated adjacent to the cathode limits the magnitude of the current. A control element is placed within the space charge so that in the normal range of operation of the device, it is always located in the negative electrostatic field of the space charge. This space charge will thereby serve to shield the control element and prevent feed back between the anode and the control element.

One structure for carrying out this method, and which structure may be considered as a preferred form for some purposes, is illustrated in Figures 1 and 2 herein. I provide a highly evacuated envelop 5 formed of a dielectric material such as glass, the envelop being free of any modifying or controlling gas, this being accomplished in the conventional manner.

The envelop is preferably made elongated in shape and at one end is provided with a pedestal of the same material indicated at 6 which serves as a supporting means for the anode and electron emitting element.

The electron emitting element is designated 7 and preferably takes the form of a helical filament which has one end supported from a lead-in conductor 8 as indicated at 9 and the other end supported from a complementary lead-in conductor 10 as indicated at 11. The filament 7 is 55

energized to an incandescent state in the usual manner by imposing a suitable potential on the conductors 8 and 10. It is to be observed that the helical filament is thus disposed substantially 5 along the longitudinal axis of the envelop or tube 5.

The control element is formed of a helical conductor 12, whose convolutions are slightly smaller 10 in diameter than those of the filament 7 and disposed in alternative relationship throughout as to always be in the space charge generated by the filament 7. The control element 12 has its opposite ends affixed as at 13 and 14 to a lead-in conductor 15 at the opposite end of the tube. Of course, the conductor 15 may pass out through 15 the pedestal 6, but for convenience the mounting and supporting structure shown in Figure 1 is to be preferred. In order to shield the conductor 15 from the anode I provide a tubular conductor 17 20 connected to the cathode through conductor 16 and engaging the pedestal 16 for the purpose of tending to make the structure less sensitive to vibration due to extraneous shocks or jars.

The anode comprises the cylindrical metallic element 18 supported by bracket wires 19, carried by a collar 20 which surrounds the pedestal 6 and is fixedly secured thereto. The anode 18 is thus supported adjacent to the locality of the filament 7 in spaced relationship thereto so as to 25 receive the stream conducting electrons which are thrown off from the incandescent filament.

Under practical operating conditions the electrons are emitted from the cathode 7 with finite 30 velocities and the space charge located immediately adjacent to the filament, in view of the positioning of the electrodes and potential impressed, serves to limit the magnitude of the current and to produce a potential gradient between the anode and cathode of such curvature that 35 there is a point of zero potential between the anode 18 and the cathode 7 and a reversal of sign 40 of the electrostatic field at this point. Thus the slope of the potential gradient at the cathode is negative. It is desirable that the control element 45 be placed back of the cathode 7 or immediately adjacent thereto so that it will always be located in the negative field created by the space charge. Thus it will be seen that when this control element or grid is placed in the negative field between the cathode and the point of zero potential 50 in the space charge, the control element is shielded from potential variations of the anode 18 occurring in the normal operation of the device.

As hereinabove pointed out when the potential 55 of the anode is gradually increased from zero to the saturation value of current, the density of the space charge and its distribution will change so that the point of zero potential between the cathode and the anode moves toward the cathode 60 and becomes coincident with it at the saturation point. For this reason it is desirable that the control element and cathode be approximately equi-distant from the anode so that the shielding effect will be present throughout the maximum 65 range of operation.

When the cathode 7 is brought to incandescence, the released electrons move into the space surrounding the filament and thus form a space charge which eventually prevents further electrons from leaving the filament, that is, the number of electrons returning to the filament becomes 70 equal to the number leaving it. When a constant positive potential of a value less than that required to produce the saturation current is applied to the anode 18 this equilibrium is disturbed

due to the migration of the electrons to the anode and it follows that a new equilibrium will be established in which the number of electrons leaving the filament becomes greater than the number returning to it. Thus, a current flows between the anode and the cathode which is limited by the space charge potential by virtue of its power to cause some of the emitted electrons to return to the filament. Thus the volume of the current passing through the device may be controlled by applying various potentials to the control element 12 for the reason that these potentials affect the electrostatic field surrounding the filament and change the magnitude and distribution of the controlling space-charge. Due to the positioning 15 of the control element adjacent to the filament I produce a greater change in current per unit change in its potential than that produced by the same change in potential of the anode and this condition must prevail in order for the device to function as an amplifier.

Figure 3 illustrates a typical current characteristic curve of the apparatus of my invention. The ordinates 21 represent anode currents and the abscissae 22 represent control element potentials, 25 the anode potential being fixed at some suitable positive value. It will be observed that the value of the anode current may be reduced to zero by impressing the appropriate negative potential on the control element.

Referring now to Figure 4, the device of this invention is shown at 5a in a circuit arrangement suitable for amplifying alternating currents. For the purpose of convenience the input circuit is indicated at 23, consisting of a primary winding 24 and a secondary winding 25 of a transformer 26 and the output side of the circuit is indicated at 26 and comprises the primary winding 27 and a secondary winding 28 of the transformer T'.

The amplifying circuit contains the device 5a 40 of this invention in which the filament or electron emitting element is shown at 7a energized by a suitable source of current 29, and a cathode is shown at 30 immediately adjacent to the filament 7a, an anode or plate being indicated at 31. The 45 source of electric potential such as a battery 32 is also arranged in the amplifying circuit.

The terminals of the primary of the transformer T are connected to a source of current to be amplified and one of the terminals of the secondary 50 25 is connected by a conductor 33 to the control element 30, the other conductor being connected to the negative side of the battery 29, this battery providing current for heating the filament 7a through the leads 8 and 10. The positive side 55 of the battery 29 is connected to the negative side of the battery 32 and the positive side of the latter is connected by conductor 34 to one side of the primary winding 27 of the transformer T'. The plate, or anode 31, is connected by conductor 35 to the opposite end of the primary 27. The secondary 28 of the transformer T' provides an output circuit for the amplified currents.

Potential variations impressed upon the control element 30 through the transformer T cause amplified current variations to occur in the anode circuit including the battery 32 and primary winding 27 and thus, through the transformer T' energy is transferred to the output circuit.

Because of the shielding effect of the space 70 charge on the control element, the circuit shown in Figure 4 will function as a suitable amplifier and will not generate oscillating currents within itself. This condition has been found to obtain with the constants of the circuit designed to 75

amplify alternating currents at frequencies as high as 15 mega-cycles per second.

The form of the invention shown in the Figures 1 and 2 is more particularly adapted for employment where uni-directional electric current is employed for heating the filament.

Referring now to Figure 5, an alternative form of the invention shown in Figures 1 and 2 more particularly is disclosed herein. A highly evacuated envelop 5d is provided having a pedestal 69 extending axially thereof. The end of the envelop or tube 5d adjacent to the pedestal is externally provided with a base 70 for the external terminals of the tube, a suitable adhesive matter 71, such as plaster of Paris, or the like, being applied for affixing the base 70 to the tube 5d in the conventional manner.

In this form of the invention I provide lead-in conductors 72 and 73 connected to the pins 74 and 75, respectively, said lead-in conductors being connected at their inner ends to the terminals of the double spiral filament 76 which forms the electron emitting device. The filament is supported by an axially extending rod 77 embedded at 78 in the head of the pedestal 69 and a suitable metallic cap or disc 79 shields the upper end of the control element 80 from the anode.

Within the filament I provide a control element 80 in the form of a cylindrical metal tube, this tube being supported by a support rod 81 embedded in the head of the pedestal 69 and additionally by a lead-in wire 82 which extends through the pedestal and connects to the terminal pin 83.

In order to shield the lead-in wires and associated elements from the anode, I provide a cylind-

rical shielding member 84 connected to the cathode as at 92 and carried by the pedestal 69 and provided with a closing partition or cap 85, apertured at 86 to accommodate the filament and control element which project therethrough.

The anode is indicated at 87 and is a cylindrical plate supported by straps 88 from a ring 89, such ring being applied fixedly to an auxiliary pedestal 90 formed at the opposite end of the tube. The anode is connected to the output side of the amplifying circuit by the lead-in conductor 91 connected at 92 to one of the straps 88.

Having thus described my invention and illustrated its use, what I claim as new and desire to secure by Letters Patent is:

1. An electron-discharge device for amplifying pulsating currents comprising a helical electron-emitting cathode and a helical control element of the same pitch as the said cathode the convolutions whereof are interpositioned and a cylindrical anode of larger diameter than the said cathode, the axes of the three elements being substantially coincident, said control element being located between the cathode and the point of zero potential in the surrounding space charge so that the cathode is electrostatically shielded from the anode.

2. An electron-discharge device for amplifying pulsating currents, comprising a helical electron-emitting cathode and a helical control element of the same pitch as the said cathode, the convolutions whereof are interpositioned and a cylindrical anode of larger diameter than said cathode, the axes of the three elements being substantially coincident.
